UNITED STATES PATENT OFFICE.

JOHN HUTCHINSON, OF HARTFORD, CONNECTICUT, ASSIGNOR TO UNDERWOOD TYPEWRITER COMPANY, OF NEW YORK, N. Y., A CORPORATION OF NEW JERSEY.

TYPE-WRITING MACHINE.

No. 891,078.

Specification of Letters Patent.

Patented June 16, 1908.

Application filed September 12, 1907. Serial No. 392,421.

To all whom it may concern:

Be it known that I, JOHN HUTCHINSON, a citizen of the United States, residing in Hartford, in the county of Hartford and 5 State of Connecticut, have invented certain new and useful Improvements in Type-Writing Machines, of which the following is a specification.

This invention relates to paper-severing 10 attachments for typewriting machines, and the object of the invention is to provide inexpensive, simplified and improved means that may be readily applied to existing machines for cutting or severing sheets from 15 a paper web.

A cutting-blade is secured at its ends to brackets or plates which are adjustably mounted upon the platen-frame ends, the blade lying along and in front of the platen. 20 Either end of the blade may be adjusted independently of the other end towards or away from the platen, so that the blade may be readily and accurately positioned and do effective work.

25 In the accompanying drawings, Figure 1 is a top view of a typewriter platen frame with my improved device applied thereto. Fig. 2 is a sectional end view of Fig. 1, and shows the paper web feeding around the platen. 30 Fig. 3 is a perspective view of the blade and brackets.

The platen 1 is rotatably mounted in the platen-frame ends 2, connected by a paper-table 3, all of the construction usual in the 35 well known "Underwood" typewriter. A bracket or plate 4, preferably of sheet metal, is mounted upon each end 2 of the platen frame, and arms 5 extend inwardly toward the platen, and downwardly inside of the 40 platen - frame ends, as at 6. Secured by screws 6^a to the downwardly - extending parts 6 are rigid arms 7. A cutting-blade 8 of some suitable hardened metal is secured at

each end by means of rivets 9 to the arms 7. The blade lies between the plates 4, in front 45 of the platen, and is inclined to the latter.

The plates 4 are provided with slots 10, through which pass screws 11 for securing them to the platen-frame ends 2, and permit shifting of the said plates 4 backwardly and 50 forwardly, together with the cutting-blade 8, towards and away from the platen, thus permitting of the insertion of a sheet or sheets of paper of different thickness between the blade 9 and the platen 1. The plates 4 are 55 shiftable one independently of the other.

The paper 14 passes from a roll 13 around the platen and up between the same and the cutting-blade. When a relatively thin paper is being used the cutting-blade 8 is set quite 60 close to the platen. However, should it be desired to use a thicker sheet of paper, or a number of sheets of paper, the blade is set outwardly or away from the platen by loosening the screws 11 and shifting the plates 65 forwardly. The blade is set above the place where the types 16 strike the platen.

Having thus described my invention, I claim:

An attachment for the platen - frames of 70 typewriting machines, comprising a pair of brackets having slots for adjustable connection to the ends of the platen frame, each bracket having an arm to extend down in front of the platen, and a cutting blade to extend along the platen and secured at its ends to said arms; the slots permitting adjustment of the ends of the blade independently of each other towards and away from the platen to accommodate difference in thickness of paper. 75 80

JOHN HUTCHINSON.
